UNITED STATES PATENT OFFICE.

THOMAS BURKE FOGARTY, OF NEW YORK, N. Y.

IMPROVEMENT IN GAS-BURNERS.

Specification forming part of Letters Patent No. 135,978, dated February 18, 1873.

To all whom it may concern:

Be it known that I, THOMAS BURKE FOGARTY, of New York, in the county and State of New York, have invented certain new and useful Improvements in Gas-Burners, of which the following is a specification:

Nature and Object of the Invention.

In burning illuminating-gas under pressure, particularly that made by an admixture of volatile hydrocarbons with atmospheric air, the inductive force of the escaping gas at the burner absorbs an additional and undue amount of the surrounding air, and causes the flame to "blow," as it is technically described. There have been various methods in use to remedy this defect by feeding the flame with an external supply of rich gas from the lower portion of the burner through openings that have been regulated and adjusted by different mechanical devices, all of which are so combined with the burner that they are operated from the outside, and are likely to be interfered with by a casual and unskilled attendant.

The object of my invention is to regulate the escape of the gas intended to serve as an external supply to the flame as near to the tip as possible, so that the escape through the accessory openings will be influenced by the same conditions of heat that effect the tip itself; and also to provide for the adjustment of the escape wholly within the burner, so that it can be adjusted only by removing the burner and with the use of tools. To accomplish this object, my invention consists in perforating the burner with a series of small holes at the base of the tip, and in providing a means of adjustment wholly within the tube of the burner.

Description of the Drawing.

To enable others skilled in the arts to which it appertains to make and use my invention, I will proceed to describe its construction and operation with reference to the drawing.

Figures 1, 2, and 3 represent modifications of the same principle of construction as applied to three patterns of burners, in each of which *a* is the tip, which may be made separate and of lava, or with the burner in any of the forms ordinarily employed. *b* is the burner-tube that is screwed upon the gas-pipe; *c*, the small openings encircling the base of the tip; *d*, the openings through which the gas passes to the external openings; and *e* is the internal regulating-valve. In Figs. 1 and 2 the position of the internal valve is adjusted by the screw-thread in the socket of the burner; and the adjustment must be effected when the burner is detached from the pipe and with the assistance of a screw-driver. In Fig. 3 the collar of the valve fits tightly the barrel of the burner, and when it is forced against the top of the interior of the barrel the adjusted minimum of extra gas passes through its holes.

Claim.

I claim as my invention—

The construction of a burner, substantially as described, in which a supply of gas external to the flame is regulated around the base of the tip by means of an internal valve that can be operated only when the burner is detached from the pipe.

THOS. B. FOGARTY.
